UNITED STATES PATENT OFFICE

155,618

DESIGN FOR A COMBINATION PORTABLE
DISPLAY AND STORAGE CASE FOR RARE
POSTAGE STAMPS

Carl P. Meyer, Cicero, Ill.

Application August 17, 1946, Serial No. 132,608

Term of patent 7 years

(Cl. D87—5)

To all whom it may concern:

Be it known that I, Carl P. Meyer, a citizen of the United States, residing in Cicero, Cook County, Illinois, have invented a new, original, and ornamental Design for a Combination Portable Display and Storage Case for Rare Postage Stamps, of which the following is a specification, reference being had to the accompanying drawings, forming a part hereof.

Fig. 1 is a front elevational view of a combination portable display and storage case for rare postage stamps, showing my new design, the case being in an open position;

Fig. 2 is a side elevational view of the case as shown in Fig. 1 with the rear drawer open;

Fig. 3 is a rear elevational view of the case; and

Fig. 4 is a side elevational view of the case in upright, closed position, the opposite side being identical therewith.

The top and bottom of the case, not shown, are plain.

My design for a combination portable display and storage case for rare postage stamps is characterized by the shallow drawer across the bottom of the back thereof in association with the cover which is hinged at the top edge of the back of the case, the resulting raised extension of the

back forming a background for the double row of filing cards inside the case, all as shown.

I claim:

The ornamental design for a combination portable display and storage case for rare postage stamps, substantially as shown and described.

CARL P. MEYER.
